UNITED STATES PATENT OFFICE.

WILLIAM E. TURNER, OF ROCHESTER, NEW YORK, ASSIGNOR TO NATIONAL FIRE
ESCAPE CORPORATION, OF ROCHESTER, NEW YORK, A CORPORATION OF NEW
YORK.

FOLDING BRACKET FIRE-ESCAPE.

1,360,831.

Specification of Letters Patent. Patented Nov. 30, 1920.

Application filed May 31, 1919. Serial No. 300,829.

To all whom it may concern:

Be it known that I, WILLIAM E. TURNER, a citizen of the United States, residing at Rochester, in the county of Monroe and State of New York, have invented certain new and useful Improvements in Folding Bracket Fire-Escapes; and I do hereby declare the following to be a full, clear, and exact description of the invention, such as will enable others skilled in the art to which it appertains to make and use the same.

This invention relates to fire escapes and the primary object of the invention is to provide an improved fire escape of compact form, which is adapted to be secured to a building adjacent to the windows thereof or other fire exits.

Another object of the invention is to provide an improved fire escape of the flexible cable type embodying a supporting reel normally positioned in a protecting housing, which is secured to the outer surface of the walls of a building, said invention also embodying an improved means for moving the reel out of the casing and for allowing a predetermined amount of the cable to unwind from said reel.

A further object of the invention is to provide an improved folding fire escape embodying a supporting reel having a cable wound thereon, by means of which persons are adapted to slide to the ground, normally positioned in a protecting casing, said reel being so arranged in the casing that when the reel is released the same will be spaced from the wall of the building, so as to effectively prevent persons sliding down the cable from bumping into the wall.

A further object of the invention is to provide improved means for holding the supporting reel in the protecting housing.

A still further object of the invention is to provide an improved device of the above character, which is durable and efficient in use, one that is simple and easy to manufacture, and one that can be placed upon the market at a reasonable cost.

With these and other objects in view, the invention consists in the novel construction, arrangement and formation of parts, as will be hereinafter more specifically described, claimed, and illustrated in the accompanying drawings, forming a part thereof, in which:

Figure 1 is a front elevation of the im-

proved fire escape, showing the same in operative position on a building,

Fig. 2 is a side elevation of the same,

Fig. 3 is a front elevation of the fire escape with the reel in its projected position showing the protecting cover and front wall of the casing removed,

Fig. 4 is a detail section taken on the line 4—4 of Fig. 3, showing the reel in its projected position in full lines and in its collapsed position in dotted lines,

Fig. 5 is a detail section through the weight, and

Fig. 6 is a detail view of the releasing means for the latches and reel.

Referring to the drawings in detail, wherein similar reference characters designate corresponding parts throughout the several views, the numeral 1 generally indicates the fire escape which includes the 75 protecting casing 2 formed of suitable sheet metal and including the upper and lower walls 3 and 4, the rear wall 5, and the front wall 6, which has the entire upper portion thereof cut away and this portion is adapted to be closed by a cover 7, which is hinged at the top edge thereof as at 8. The lower edge of the protecting cover 7 carries inwardly extending horizontal shelf 9, the purpose of which will be hereinafter more 85 fully described. The casing is positioned on the wall 10 of a building adjacent to the window or other fire exit 11 by means of an eye-bolt 12 that extends entirely through the wall 10 and is locked in position by 90 means of the nut 13 turned on the threaded end of the same. A shaft 14, is journaled in suitable bearings 15 carried by the rear wall 5 of the casing adjacent to the lower end thereof and the terminals of this shaft extend outward through the side walls of the casing and have keyed thereto the angular arms 16, which have the terminals thereof bent inwardly to form lugs 17 which are adapted to engage the extreme lower edge of 100 the hinged door 7, so as to normally hold the same in closed position. The shaft 14 has also keyed thereto the spaced upwardly extending arms 18, which are arranged in the casing and have their upper ends inclined 105 inwardly toward each other and the upper ends of these arms have secured thereto ears 19, which support the U-shaped member 20, the terminals of the arms of which have the shaft 21 journaled therein. The shaft 21 110

has secured thereto the reel 22 on which the flexible cable 23 is wound. The central portion of the bight portion of the U-shaped member 20 has formed therein an eye 24, 5 which receives one end of the flexible chain 25, the opposite end of which is secured to the eye-bolt 12, and this chain limits the downward movement of the arms 18, when the shaft 14 is rocked.

- 10 As shown in the dotted line position in Fig. 4, the arms 18 and the reel 22 are adapted to be normally positioned in the casing 2, but owing to the fact that the reel 22 is off or beyond the pivot point of the 15 arms, the same normally tends to throw the arms outwardly, and to open the hinged cover 7. As stated, the hinged cover 7 is normally held in closed position by the pivoted angular latch arms 16 and the same are 20 held in engagement with the extreme lower edge of the door 7 by means of a flexible rope 26 which has one end fastened to one 25 of the latch arms at the angled portion thereof and is threaded through an opening 27 formed in the wall 10. The free end of the flexible rope 26 carries the eye 28 which is adapted to be positioned over an outwardly extending pin 30 secured in the wall 10. This effectively holds the angular 30 latch arms in engagement with the hinged door 7 to hold the same closed and the reel 22 and the arms 18 against movement.

When it is desired to release the latch arms and allow the reel to move outward, 35 the eye 28 is moved off of the pin 30 which permits the reel to throw the door open.

A vertical tubing 32 extends downward through each floor of the building adjacent to the windows or fire exits thereof and this 40 tubing rotatably supports a rod 33 which has outwardly extending operating handles 34, one of which is positioned adjacent each window or fire exit of the building. The tubing 32 is provided with arcuate slots to 45 permit the handles 34 to be turned in the tubing and thus rotate the rod 33. The upper end of the rod is provided with an arm 35, positioned adjacent to the lug 30 and this arm is adapted to engage the eye 50 28 and when the rod is turned, the arm will be turned and thus move the ring off of the lug 30 and permit the reel to move outward of the casing.

The free end of the cable 23 has secured 55 thereto a weight 36, which is normally positioned on the shelf 9 carried by the lower edge of the door 7 and when the catches are released and the door is thrown open by the weight of the reel, the same will be 60 thrown from the shelf and thus unwind the cable from the reel and hold the cable taut and permit the persons to readily slide down the cable to the ground.

A stop 37 is provided for permitting a 65 certain amount of the cable to escape from

the reel and this stop includes a lever 38 pivoted at its inner end as at 39 to one of the arms 18 and the opposite end of the lever is provided with a sharpened portion 40, which is adapted to normally rest and engage 70 the outer edge of one of the side walls of the reel 22, and this side wall is provided with a plurality of notches 41, and when the end of the lever engages in one of the notches the reel is held against rotation. A 75 downwardly extending rod 41' is carried by the lever 38 and this rod engages the cable 23 carried by the reel, and holds the lever out of engagement with the notches. The rod 41' is set so as to permit the desired 80 amount of cable to be paid from the reel, and after this amount has been paid therefrom and is moved from under the rod, the lever 38 will fall and thus engage in one of the notches to prevent further rotation 85 of the reel.

In applying the device to a building, the height of the same is determined, and the length of the cable allowed to be paid from the reel is accordingly governed. 90

From the foregoing description, it can be seen that an improved fire escape of compact form of the flexible cable type is provided which is adapted to be secured to a building and will not in any way disfigure or 95 alter the appearance thereof and at the same time provides effective means for allowing persons to escape from the building when necessary.

In practice, I have found that the form of 100 my invention illustrated in the accompanying drawings and referred to in the above description, as the preferred embodiment, is the most efficient and practical; yet realizing the conditions concurrent with the 105 adoption of my device will necessarily vary, I desire to emphasize that various minor changes in details of construction, proportion and arrangement of parts may be resorted to, when required, without sacrificing 110 any of the advantages of my invention as set forth.

What I claim as new is:

1. A fire escape comprising a casing, a shaft rotatably mounted in the casing, a pair 115 of arms keyed to the shaft, a drum rotatably carried by the arms, said drum being normally adapted to extend out of said casing, a hinged cover for said casing arranged to engage said drum to hold the same within 120 the casing, when the lid is in its closed position, a pair of catches carried by said shaft and arranged to engage said lid to hold the same in its closed position, and means for releasing said catches so as to permit the lid 125 to swing outward.

2. A fire escape of the class described including a casing, a shaft journaled in said casing adjacent to the lower end thereof, a pair of arms keyed to said shaft, a drum ro- 130

tatably carried by the upper ends of the arms and normally tending to throw the arms outward, a cable wound upon said drum, a weight carried by said cable, a hinged lid 5 carried by the casing and arranged when the same is in its closed position to hold the arms within the casing, an inwardly extending shelf formed on said lid, said weight being adapted to rest upon said shelf when 10 the lid is in its closed position, catches engaging said lid adjacent to the lower edge thereof to hold the same in its closed position, and means for releasing said catches.

3. A fire escape comprising a casing, a 15 shaft rotatably mounted in the casing adjacent to the lower end thereof, a pair of arms keyed to the casing, a drum rotatably carried by the upper ends of the arms and

normally tending to throw the shaft outward, means for limiting the outward movement of the reel, catches carried by the shaft arranged to engage the extreme lower edge of the door, flexible means carried by the catches, a ring carried by the ends of said flexible means, a lug adapted to receive 25 said rings to hold the catches in engagement with the door, and means to move said rings off of said lugs so as to permit said reel to open the cover and allow the reel to be projected therefrom.

In testimony whereof I affix my signature in presence of two witnesses.

WILLIAM E. TURNER.
